UNITED STATES PATENT OFFICE

JOHN YOUREK, OF CHICAGO, ILLINOIS

DESIGN FOR A HAT

Application filed June 19, 1931. Serial No. 40,275. Term of patent 7 years.

To all whom it may concern:

Be it known that I, JOHN YOUREK, a citizen of the United States, residing at Chicago, in the county of Cook and State of Illinois, have invented a new, original, and ornamental Design for a Hat, of which the following is a specification, reference being had to the accompanying drawings, forming part thereof.

Fig. 1 is a perspective view of the hat showing my new design; and

Fig. 2 is a plan view of the same.

I claim:

The ornamental design for a hat as shown.
JOHN YOUREK.
